[57] CLAIM

The ornamental design for a wall mounted sign, as
shown and described.

DESCRIPTION

FIG. 1 is a front elevational view of a wall mounted sign
showing my new design;

FIG. 2 is a rear elevational view thereof;

FIG. 3 is a top plan view thereof, the bottom plan view
being identical to this view; and

FIG. 4 is a side elevational view showing the right side
thereof, the left side elevational view thereof being
identical to this view.

FIG. 4.

FIG. 1.

FIG. 2.

FIG. 3.
